UNITED STATES PATENT OFFICE

ELMER ROBBINS, OF PORTLAND, OREGON

ADJUSTABLE ARM CHAIR

Application filed January 29, 1930. Serial No. 424,204.

The object of my invention is to provide an upholstered arm chair which is adjustable to any convenient position of the occupant; that is to say, from an upright to a more or less lounging position, the adjustment of the chair being effected by a mere change in position of the occupant. In other words, by the mere act of the occupant moving forward, the back of the chair will be swung forward and the seat moved forward and inclined downward, so that the back and the seat become arranged for reclining therein. If when the chair is adjusted to lounge in the same, the seat remains in horizontal position, or is tilted upward at its forward end, the occupant will generally not be as comfortable as he would be if his feet are brought close to the floor.

A further object of my invention is to arrange the mechanical devices of my chair that the same will be concealed, and thus not in anywise detract from the appearance of the chair; in other words, to maintain in the chair in all adjustments of its seat and back-rest, a non-distorted, attractive arm chair appearance. Also to make the mechanical devices of simple and durable construction.

In one embodiment of my invention, the same consists of the combination in an adjustable arm chair, of a frame comprising fixed side and elevated back sections, with the side sections including forward arm rest portions and integral rising inwardly extending back portions, there being included a seat and a back-rest hinged thereto, with the back-rest pivoted at the top pendant from the upper end of the back frame section. The seat is supported at the forward end on means which facilitates limited longitudinal movement of the seat in the chair frame so that the occupant of the chair, by change of position, may adjust the chair to sit upright or more or less lounge therein. The whole chair is upholstered in a manner to conceal the operable supports of the seat and back-rest so that in all possible adjustments of the seat and back-rest the chair presents the appearance of a non-distorted arm chair.

The details of my chair, as well as some of the possible variations in its construction, are

hereinafter described with reference to the accompanying drawings, in which:

Fig. 1 shows a perspective view of my chair when completed and illustrates by broken lines the relative positions assumed by its back and seat;

Fig. 2 shows a perspective view of the skeleton frame of my chair;

Figs. 3 and 4 show the back and seat frames of my chair removed from the chair frame;

Fig. 5 shows a perspective view of the chair frame with the back and seat frames removed therefrom;

Fig. 6 shows a side elevation of the chair frame and illustrates by broken lines the positions assumed by the back and seat when adapted to a reclining position of the occupant;

Fig. 7 shows a section taken on the line 7—7 of Fig. 6;

Fig. 8 shows a central, longitudinal section through the chair frame and illustrates a modification of the seat supporting means;

Fig. 9 shows a central, longitudinal section of a further modification of my chair, in which the back is formed in two sections, one stationary and the other movable;

Fig. 10 shows in a similar view to Fig. 9 the seat and back adjusted to the reclining position;

Fig. 11 shows a front elevation of my chair and illustrates the details of construction of this modification; and

Fig. 12 shows a fragmentary, perspective view of this modification, illustrates the details of construction of the back frame and its connection with the chair frame.

Referring now to Figs. 1 to 7, inclusive: My invention comprises a skeleton chair frame *a* consisting of side members *b*, cross member *b'* at the seat portions, and a transverse rod *c* at the top of the back portion.

The front of the seat portion is provided with a U-shaped transverse rod *e*, pivotally mounted at its ends as at *e'* in the members *b*, in recesses *f* adapted to accommodate the sides of the said U-shaped rod *e* and permit an arcuate movement thereof, without interfering with the corresponding movement of the seat frame, hereinafter described.

Back and seat frames *h*, *i*, respectively, are hingedly connected together as at *j*, see Figs. 3 and 4. An elongate transverse notch *k* is provided in the rearward surface of the back frame *h* adjacent the top, by which the back frame is pivotally mounted on the said rod *e*, and notches 1 are provided in the underside of the seat frame *i*, adjacent its front, adapted to be mounted on the U-shaped rod *e* and by which the seat frame *i* is swingingly and pendently supported.

Resilient elements or bumpers *p* are provided on the ends of the rear transverse members *b'* for cushioning the rearward swing of the seat frame.

16 By this construction, the movement of the seat frame forward will cause the back frame to swing forward also and the seat to be inclined downward, as illustrated in Figs. 6 and 8 to conform with the more natural reclining position of the occupant.

Thus the usual springs and upholstering, having been provided as illustrated in Fig. 1, the occupant of the chair may, by merely shifting his weight backward or forward in 25 the chair, change from an upright to a reclining position or the reverse, as his fancy may dictate.

Referring now to Fig. 8: I show a slightly modified embodiment of my chair, in that the seat frame 3 is provided with notches 3^a and is supported on a U-shaped transverse rod 2, the equivalent of the rod *e* previously described, but is mounted to rotate in bearings 4, secured on the underside of the side portions of the chair frame. This construction may at times be preferable in that no recesses, equivalent to the recesses *f* in the side members are required, and possible wear on the adjacent upholstered surfaces of the chair is eliminated.

In Figs. 9 to 12 is shown a further modification of my invention, in that the back frame 17 is relatively shorter and is supplemented by a stationary back section 18 of the chair frame. The back section 17 is pivotally connected below the section 18 at its upper end on pintles 19 seated in notches 19^a in the side members 20; the seat frame 11 being mounted pendently on the U-shaped cross rod 12, as previously illustrated in Figs. 1 to 7.

I claim:

1. In an arm chair of the character described, a frame including fixed sides and elevated back sections, a seat and a back-rest hinged thereto, said back-rest being pivoted at the top pendant from the upper ends of the back sections of the chair frame, a transverse angular rod rotatably supported at its ends between the sides of the chair frame, such rod supporting the forward end of said seat, the interior of the sides of the chair frame being recessed to receive and house the angular ends of said rod, the under side of the seat frame being provided with seats in which the rod bears, the whole chair being upholstered, whereby said operable supports of the seat and back-rest are concealed and an arm chair appearance is maintained in all adjustments of said seat.

70 the seat frame being provided with notches and said rod bearing in said notches, the whole chair being upholstered, whereby said operable supports of the seat and back-rest are concealed and an arm chair appearance is maintained in all adjustments of said seat.

2. In an arm chair of the character described, a frame including fixed sides and elevated back sections, a seat and a back-rest hinged thereto, said back-rest being pivoted at the top pendant from the upper ends of the back sections of the chair frame, a transverse angular rod rotatably supported at its ends between the sides of the chair frame, such rod supporting the forward end of said seat, the interior of the sides of the chair frame being recessed to receive and house the angular ends of said rod, the under side of the seat frame being provided with notches and said rod bearing in said notches, and means limiting the rearward movement of said seat to the alignment of the back-rest with the back of the chair frame.

3. In an arm chair of the character described, a frame including fixed sides and elevated back sections, a seat and a back-rest hinged thereto, said back-rest being pivoted at the top pendant from the upper ends of the back sections of the chair frame, a transverse angular rod rotatably supported at its ends between the sides of the chair frame, such rod supporting the forward end of said seat, the interior of the sides of the chair frame being recessed to receive and house the angular ends of said rod, the under side of the seat frame being provided with seats in which the rod bears, the whole chair being upholstered, whereby said operable supports of the seat and back-rest are concealed and an arm chair appearance is maintained in all adjustments of said seat.
